(57) **CLAIM**

The ornamental design for a cold brewing pot, as shown and described.

DESCRIPTION

FIG. 1 is a front isometric view of a cold brewing pot showing our new design.

FIG. 2 is a top view of the cold brewing pot.

FIG. 3 is a bottom view of the cold brewing pot.

FIG. 4 is a front view of the cold brewing pot.

FIG. 5 is a rear view of the cold brewing pot.

FIG. 6 is a right side view of the cold brewing pot.

FIG. 7 is a left side view of the cold brewing pot; and, FIG. 8 is a cross-sectional view taken along line 8-8 of FIG. 2.

The broken line portions in the drawings depict portions of the cold brewing pot that form no part of the claimed design.

1 Claim, 8 Drawing Sheets
